Primary Examiner — Paula Allen Greene

(57) **CLAIM**

The ornamental design for a headphone holder, as shown and described.

DESCRIPTION

1. Headphone holder
- 1:1 Front Perspective
- 1:2 Rear Perspective
- 1:3 Front View
- 1:4 Rear View
- 1:5 Left Side View
- 1:6 Right Side View
- 1:7 Top View
- 1:8 Bottom View

1 Claim, 8 Drawing Sheets(56)
